UNITED STATES PATENT OFFICE.

EDWARD B. PEOPLES, OF OTOE, NEBRASKA.

GRAIN-CAR DOOR.

Application filed April 5, 1924. Serial No. 704,404.

To all whom it may concern:

Be it known that EDWARD B. PEOPLES, a citizen of the United States, residing at Otoe, in the county of Otoe and State of Nebraska, has invented certain new and useful Improvements in Grain-Car Doors, of which the following is a specification.

This invention relates to a grain car door and has for its principal object to provide a means for preventing the grain from accidentally being discharged through leakage as frequently happens with the grain doors now in use, means being further provided for enabling the operation of the door in such a manner as to facilitate the easy discharge of the grain from the car without any loss.

A still further object of the invention is to provide a grain car door of the above mentioned character, wherein the same is adapted to be constructed in sections, fastening means being associated therewith for securely holding the door in a closed position and covering the door opening in such a manner as to provide a tight fit around the door frame so as to prevent the possibility of the grain leaking therethrough while the car is in motion.

A still further object is to provide a grain car door of the sectional type wherein means is provided for slidably supporting the same in position on the car, bracing means being associated with the grain car and forming a guide means for holding the sections in vertical alignment when the same are moved rearwardly to uncover the door opening.

A further object is to provide a grain car door of the above mentioned character which is simple in construction, inexpensive, strong and durable and further well adapted for the purposes for which it is designated.

Other objects and advantages of this invention will become apparent during the course of the following description.

In the accompanying drawings forming a part of this specification, and in which like numerals designate like parts throughout the same,—

Figure 1 is a longitudinal sectional view of a portion of a grain car showing the door and braces positioned thereon in side elevation, the door being in a closed position.

Figure 2 is a longitudinal section taken on line 2—2 of Fig. 1.

Figure 3 is a vertical section taken on line 3—3 of Fig. 1.

Figure 4 is a fragmentary sectional view taken on line 4—4 of Fig. 1.

Figure 5 is a detail perspective view of the lower portion of the door showing the grain discharge opening therein.

Figure 6 is a detail sectional view showing the locking means associated with the door and frame therefor, and

Figure 7 is a detail view of the closure plate and fastening means therefor, shown disassembled.

Figure 8 is a detailed section as seen on the line 8—8 of Fig. 1.

In the drawings, wherein for the purpose of illustration is shown the preferred embodiment of my invention, the numeral 1 designates generally the grain car which is of the usual construction and is provided with the door frame 2 and opening therefor. 70 The door frame 2 has its rear side wall 3 divided as shown in Fig. 2 of the drawings for the purpose to be hereinafter more fully described.

My grain car door designated generally 80 by the numeral 4 comprises the lower and upper sections 5 and 6 respectively. The lower section 5 is provided with a grain discharge opening 7 and the latter is preferably formed in the reinforcing wall 8 secured to the rear face of the lower section 5, a similar reinforcing wall 9 being associated with the upper section 6. As will be read- 85

ily seen in Fig. 5 of the drawings, the strips of wood which form the outer face or wall 90 of the lower section 5 extend vertically, whereas the reinforcing wall 8 secured to the rear face thereof has the strips thereof extending transversely thereto, the purpose of which is to prevent the possibility of the lower section of the door from warping. The same construction is also provided in connection with the upper section of the grain car door 4.

The grain discharge opening 7 has a suitable closure plate 10 pivotally mounted on the pin 11 on the outer face of the reinforcing wall 8 and a suitable latch 12 is pivotally associated with the closure plate 10 and is

adapted for cooperation with the locking element 13 which extends upwardly from the lower door section 5 in the manner as shown more clearly in Figs. 4 and 5 of the drawings, the purpose of the closure plate 10 and the locking means therefor being to prevent the accidental opening of the closure plate when the car is filled with grain, thus preventing the leakage of grain there-through. The upper section 6 and the reinforcing wall 9 therefor has a longitudinally extending rib 14 formed on the bottom thereof and this rib is adapted to be received in the longitudinally extending groove 15 formed in the upper edge of the lower section 5 and the reinforcing wall 8 therefor. A suitable lining of metal conforming to the shape of the bead or rib 14 and the cooperating channel or groove 15 such as is shown at 16 and 17 respectively in the drawings is provided for the purpose of forming a means whereby the upper section may be moved with respect to the lower section whenever it is necessary. Furthermore, the purpose of this construction is to provide a tight fit between the upper and lower sections of the grain car door thus avoiding any possibility of the grain leaking there-between. Heretofore it has been found necessary in connection with grain cars to provide a suitable lining of paper or the like over the door to prevent the possibility of any grain from leaking or otherwise being accidentally discharged from the car through the door.

Also with the grain car doors heretofore in use it has been necessary to destroy the entire lower section of a sectional car door after the car has reached its destination in order to enable all of the grain to be discharged from the car. This necessitated the replacing of the broken section by an entirely new section and also having to reline the entire door each time it was desired to transport grain from one place to another. By providing a grain car door of the character shown and hereinafter to be more fully described, this unnecessary expense and labor has been eliminated and furthermore the proper sealing of the grain against accidental loss due to leakage is assured.

The sections of the door are adapted to move longitudinally in order to uncover the opening in the door frame and this is accomplished by providing the usual door hanger 18 which extends longitudinally adjacent the upper portion of the side of the car over the opening in the well known manner. The upper section 6 is furthermore provided with a number of upstanding brackets or the like shown at 19 in the drawings and these brackets support the pulley wheels 20. The latter are adapted to engage the upwardly extending flange 21 provided on the hanger 11 whereby the upper section may be freely

moved on the door hanger when the handle 22 is actuated for the purpose of uncovering the upper portion of the door frame opening whenever desired.

To further facilitate the free slidable movement of the lower section 5, the latter is provided with a series of rollers 23 which cooperate with the bottom of the grain car 24, the rollers being preferably supported in the cut-out portions 25 in the manner as shown in Fig. 3 of the drawings. The bottom 24 of the grain car is further provided with the usual guide flanges 26 and 27 respectively between which operate the lower section of the grain car door 4. A handle 28 similar to the handle 22 is secured to the lower section 5 in order to enable the same to be readily moved.

Extending vertically between the bottom and top of the grain car and to one side of the door frame 3 are the vertical standards 29. Diagonally extending braces 30 are adapted to be disposed between the spaced standards 29 and are secured thereto by means of the angle irons 31 in the manner as shown in Fig. 1 of the drawings. Auxiliary bracing rods 32 are further provided and these bracing rods extend vertically through the bottom of the car door and the upper portions of the diagonally extending braces 30 and also through the upper portion of the car 1. The vertical standards 29 are arranged on the inner opposed faces of the side of the car in such a manner as to provide a guide means therebetween for receiving the sections of the grain car door when the latter is moved to uncover the opening in the door frame when grain is to be discharged or the car is to be filled.

For the purpose of securing the sections of the door in a locked position while the same cover the door frame opening, I provide the fastening means such as is more clearly shown in Fig. 6 of the drawings, and the same comprises a slotted plate 33 which has its outer end bent upwardly as shown at 34 and this plate is adapted for slidable movement through an opening formed in each of the sections of the door adjacent the partition 3, a suitable bracket 35 being secured to the inner partition, and a locking pin 36 secured to the outer partition adjacent the outer face of the door sections and normally the slotted extension 34 rests on the projection 36. In this manner the door sections are held in a locked position against longitudinal movement and whenever it is necessary to open the door or either of the sections thereof, the plate 33 is raised upwardly so that the pin 36 will be caused to be brought into registry with the elongated slot 37 formed in the plate 33 and by pulling outwardly on the upstanding portion 34, the inner end of the plate will be caused to become disengaged from the bracket 35

whereby the door section may be free to move within the side of the car in order to open the same.

- It will thus be seen from the foregoing 5 description, that a grain car door has been provided which may be easily and efficiently operated to open or close the door opening of the car, means being provided for locking the door against accidental opening 10 whereby the loss of grain is prevented and furthermore the construction of the door sections are such as to enable the same to be moved longitudinally and independently of each other as the case necessitates.
- 15 From the foregoing description of the construction of my improved apparatus, it will be seen that I have provided a simple, inexpensive and efficient means for carrying out the objects of the invention, and while 20 I have particularly described the elements best adapted to perform the functions set forth, it is obvious that various changes in form, proportion, and in the minor details

of construction may be resorted to, without departing from the spirit or sacrificing any 25 of the principles of the invention.

Having thus described my invention, what I claim is:

The combination with a grain car door provided with a grain discharge opening 30 and further provided with a horizontal ledge adjacent the discharge opening, a plate valve pivoted to the door and normally overlying the discharge opening, a bifurcated element hingedly carried by the valve 35 and being disposed at a point diametrically opposite the point of pivotal connection of the valve and door, a threaded element projecting from the ledge and adapted to receive the bifurcated element, and a wing nut 40 threaded upon the threaded element and engaging the bifurcated element and thereby holding the plate valve against accidental pivotal movement.

In testimony whereof I affix my signature.

EDWARD B. PEOPLES.
